UNITED STATES PATENT OFFICE.

FREDERIC A. CURTIS, OF ANDERSON, INDIANA, ASSIGNOR, BY DIRECT AND MESNE ASSIGNMENTS, OF THREE-FOURTHS TO WILLIAM J. LITTLE, OF SAME PLACE, FRANK J. LEY, OF GAS CITY, AND THOMAS K. CLARK AND LEWIS N. COOK, OF MARION, INDIANA.

PROCESS OF CONSUMING SMOKE.

SPECIFICATION forming part of Letters Patent No. 663,119, dated December 4, 1900.

Application filed February 26, 1900. Serial No. 6,441. (No model.)

To all whom it may concern:

Be it known that I, FREDERIC A. CURTIS, a citizen of the United States, residing at Anderson, in the county of Madison and State of Indiana, have invented a certain new and useful Process of Consuming Smoke; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to the process of utilizing the combustible elements in smoke that is thrown off from furnaces in which there is imperfect combustion of coal by which smoke and oil together are utilized for generating heat.

The objects of the invention are to attain the greatest economy in the use of coal as a fuel and to economically abate the smoke nuisance caused by imperfect combustion due to various causes, such as improperly-constructed furnaces, imperfect draft devices, or unskilful handling of the coal.

The invention consists in a new and novel process of drawing the smoke and unconsumed gases of combustion through continuous ducts from the furnace to a smoke box or receptacle, mixing atomized oil and air with the smoke and gases, and then forcing the product through a duct to a separate furnace, in which it is consumed and utilized as heat and, if desired, under the same boiler which is served by the furnace in which the coal is consumed.

In carrying out my invention practically I may make use of various means, such as variously-shaped walls, pipes, dampers, fans, atomizers, &c.

Hitherto the perfect combustion of bituminous coal in boiler-furnaces has been accomplished only by employing various expensive or troublesome devices, in most cases requiring a separate steam-boiler for supplying an injector or similar spraying nozzle device, with the result that such apparatus, after having been tried, for obvious reasons have been

abandoned. My process differs from such in that I employ neither a steam-jet nor a jet of compressed air, which in most cases would be impracticable, especially in starting fires in the furnaces, and I effect a more perfect mixing of the unconsumed smoke and gases with the oil and air at a moderate temperature by simple mechanical operations which may be carried on by manual force when there may be no available mechanical power.

Referring to the drawings, which illustrate such means and appliances which may be employed in practically carrying out my invention, Figure 1 represents a front elevation of a common type of steam-boiler and its setting and furnace, but embodying improvements whereby my process may be adapted to a single boiler and furnace; Fig. 2, a side elevation with parts broken away and parts shown in vertical section approximately on a line *h* in Fig. 1; Fig. 3, a horizontal sectional view taken approximately on a line *a a* in Fig. 1; Fig. 4, a horizontal sectional view taken as on a line *b b* in Fig. 1; Fig. 5, a transverse sectional view of the atomizer, and Fig. 6 a vertical transverse sectional view taken as on a line *d d* in Fig. 2.

My process may be employed either in connection with a single boiler or with any or each two of a battery of boilers. For the purposes of this description a single boiler is shown.

A designates the setting embracing the walls, furnace, &c., of common form; *B*, the boiler of the cylindrical type, having tubes for the passage of heat and smoke through the water-space of the boiler; *C C'*, the furnace, which is divided by a wall or partition *F* longitudinally, the wall extending to the bottom of the ash-pit, preferably, so as to constitute two separate furnaces, the furnace *C'* having grates *e* and the adjacent furnace also preferably having grates. The wall *F* extends back over the bridge-wall *B'* and up to the boiler and also divides the return-flue at the rear end of the boiler, so as to provide separate chambers *D* and *D'*, corresponding to the double furnaces, which causes the heat and gases from one furnace or from one side

of the divided furnace to pass through one-half of the boiler-tubes at the same side of the central partition-wall F, while the gases from the other furnace pass through the tubes 5 at the opposite side of the wall. At the front of the boiler the smoke-box is also divided by a vertical central partition F', dividing the same into two chambers E and E', the latter having a closed top F², which may, however, 10 have a damper, so as to open a direct way to the chimney G when desired, while the former is open to a chamber E², communicating with the chimney. In utilizing the common type 15 of chimney having a large diameter I insert a damper, so as to reduce the strength of the draft, it being only necessary in my process to provide a vent for disposing of the fumes from combustion and the air from a fan or blower, so that in new plants a high chimney 20 is unnecessary.

From the smoke-box E' a duct H leads to an exhausting-blower I, to which is connected a duct H', leading to the furnace C. An open branch J is connected to the duct H, 25 into which oil is fed through a pipe M from a tank N, and interposed in the branch J or at any other suitable point is an atomizer L, which may comprise either stationary or movable plates interposed in the path of the oil. 30 Also the oil may be taken either directly into the fan or blower or into the duct H, as may be desired, provided that it shall be atomized and thoroughly mixed with the smoke and gases that are drawn from the coal-consuming furnace and forced into the gas-burning furnace. With the oil also a suitable amount 35 of atmospheric air is admitted and conveyed to the gas-burning furnace C.

In atomizing the oil, which is preferably 40 crude petroleum or the residuum therefrom, the most perfect results are attained in the use of the mechanical atomizer L, through which the smoke, the oil, and the air (in order to obtain oxygen) are drawn in whirling or cross currents, so that the oil may be not only 45 thoroughly broken up, but perfectly mixed with the smoky gases, all of which are not sufficiently heated as to cause deposits in the ducts, which would be detrimental in restricting 50 the passages and causing friction, as in the case when the smoke and oil are delivered through passages at high temperatures. My experiments have led to the discovery that the smoke may be practically all consumed 55 after having been cooled somewhat in passing through the first boiler and the ducts and then with the oil reheated to the combustion-point in the second furnace.

In operation a coal-fire is kindled in the 60 first or coal-burning furnace C', and the exhausting-blower being put in operation the smoke and unconsumed gases are drawn from the furnace, cooling somewhat in the passages, through the flue D', the boiler-tubes communicating with the flue D', and through the smoke-box E' into the duct H and thence into

the exhaust-blower, by which the product comprising the gaseous fuel is forced through the duct H' into the second of the required pair of furnaces C, where complete combustion 70 takes place, or the gaseous fuel may be conducted to a more remotely situated furnace for consumption, in which case both the first and second furnaces and boilers may be of the ordinary type, provided only that the first 75 or coal-burning furnace shall have communication with a duct, as H, in lieu of the chimney. In the passage of the gases and smoke from the coal-fire through the ducts I cause oil, preferably crude petroleum, to be atomized in whirling or crossing currents by baffle-plates at low temperature, and mixed therewith in order to render the product combustible at practicable temperatures, as the unburned gases and smoke could not otherwise 80 be consumed except in a degree of heat hitherto found to be inconvenient under existing conditions. In thus atomizing oil in a current of otherwise (under ordinary conditions) incombustible refuse from a furnace a new 85 and economical compound of gaseous elements is produced which may be completely consumed in a common type of furnace, thereby utilizing every possible heat unit in the fuel. It is well known that valuable properties in smoke have hitherto been wasted, as well as a nuisance maintained through the emission of smoke and soot from furnace-chimneys in residence districts, and my invention is therefore of the highest degree of utility. 90

Having thus described my invention, what I claim as new, and desire to secure by Letters Patent, is—

1. The process of consuming smoke as fuel, consisting in drawing smoke from a furnace, 105 then atomizing oil at its normal temperature in whirling or crossing currents and simultaneously reducing the temperature of the smoke and mixing the same with the atomized oil, then forcing the resultant mixture at low 110 temperature into a furnace, and then igniting the oil elements of the mixture whereby the smoke may be consumed.

2. The process of consuming smoke and unburned gases of imperfect combustion, consisting in drawing off the smoke and gases from a coal-burning furnace through the heating-channels, then breaking up or atomizing oil and mixing the same and atmospheric air at their normal temperatures with the smoke 120 in whirling or crossing currents, then causing these elements to be further mixed, then forcing the resultant mixture into a furnace where the oily elements thereof are ignited and the temperature of the whole raised thereby to the combustion-point, thereby consuming the smoke. 125

3. The improved process of consuming smoke as a fuel, which process consists in intercepting the smoke after having passed 130 through the heating-channels from a furnace, then reducing the temperature of the smoke,

then atomizing or breaking up oil at its normal temperature in whirling or crossing currents and simultaneously mixing the same with the smoke and also with atmospheric air 5 at its normal temperature, then forcing the mixture into a furnace, and then raising the temperature of the smoke by igniting the oily elements of the mixture and thereby consum-

ing the smoke and other elements of the mixture.

In testimony whereof I affix my signature in presence of two witnesses.

FREDERIC A. CURTIS.
